UNITED STATES PATENT OFFICE.

BENJAMIN F. CROW, OF NEBRASKA CITY, NEBRASKA.

HARROW.

SPECIFICATION forming part of Letters Patent No. 313,474, dated March 10, 1885.

Application filed September 27, 1884. (No model.)

To all whom it may concern:

Be it known that I, BENJAMIN F. CROW, a citizen of the United States, residing at Nebraska City, in the county of Otoe and State of Nebraska, have invented certain new and useful Improvements in Harrows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has relation to reversible harrows; and it consists in the novel construction and arrangement of its parts.

In the accompanying drawings, Figure 1 is a perspective view of two of my harrows attached to a double-tree. Fig. 2 is a detail side view showing the tooth attached to the angle-bar. Fig. 3 is a sectional view of Fig. 2 cut through on the line *x x*.

My invention is described as follows: The bars *a*, to which the teeth are attached, are made of angle-bar iron. They are secured together by means of the cross-bars *b* and *b'*.

These harrows, when completed, are attached to the double-tree *c*, by means of the clevis-irons *c'*, and when attached to the double-tree *c* by these clevis-irons *c'* the teeth *d* stand perpendicular in relation to the harrow.

These harrows are also provided at their other end with clevis-irons *c''*, by which they may be attached to said double-tree *c*, in which case the teeth *d* will set backward at an angle of about thirty degrees. (See Fig. 2.) This tooth *d* is held against the face of the perpendicular flange *a'* of the angle-bar *a* by a strap, *e*, which fits over the said tooth, giving it room to play backward about thirty degrees. The middle part, *e'*, of the strap *e* is raised by two right-angle elbows, *e'' e'''*, which make a slot for the tooth *d* to play in. The tooth *d* is straight

and pointed and the body square, has a shoulder, *d'*, and neck *d''*, the upper end of which is turned down at a right angle to form a head, *d'''*, and it is completely finished before being put in the bar *a*, which allows it to be formed under a drop-hammer, and does away with all hand-work on it.

In the upper or horizontal flange of the bars *a* are perforations *f* for the neck *d''* of the tooth *d* to pass through. This tooth has a shoulder, *d'*, which rests against the lower face of the horizontal flange of the angle-bar *a*. When the tooth *d* is put in place, the head *d'''* rests against the upper face of the horizontal flange of the angle-bar *a*. Thus the tooth is prevented from coming out, and the shoulder *d'* prevents it from being driven up higher in the perforations *f*, while its lower end is permitted to play in the slot left between the raised part of the strap *e* and the perpendicular flange of the angle-bar.

Having thus described my invention, what I claim as new, and desire to secure by Letters Patent, is—

In a reversible harrow, the combination of angle-bar *a*, having perforations *f*, with tooth *d*, having shoulder *d'*, resting against the under face of the horizontal flange of the said angle-bar *a*, and having neck *d''*, passing through said perforations *f*, and its upper end or head, *d'''*, resting on the upper face of said flange, and strap *e*, having a raised center, *e'*, secured to the perpendicular flange of said angle-bar by nuts and bolts or rivets *g*, substantially as shown and described, and for the purposes set forth.

In testimony whereof I affix my signature in presence of two witnesses.

BENJAMIN F. CROW.
